UNITED STATES PATENT OFFICE

162,622

TRICYCLE

Daniel R. Boone, Portland, Oreg.

Application June 24, 1949, Serial No. 3,497

Term of patent 14 years

(Cl. D34—15)

To all whom it may concern:

Be it known that I, Daniel R. Boone, a citizen of the United States, residing at Portland, in the county of Multnomah and State of Oregon, have invented a new, original, and ornamental Design for Tricycles, of which the following is a specification, reference being had to the accompanying drawing, forming part thereof.

Figure 1 is a side view of a tricycle showing my new design.

Figure 2 is a plan view thereof.

Figure 3 is a rear view thereof.

I claim:

The ornamental design for a tricycle, as shown.

DANIEL R. BOONE.
